UNITED STATES PATENT OFFICE.

EDWARD KENDALL, OF CAMBRIDGEPORT, MASSACHUSETTS.

APPARATUS FOR EXTINGUISHING FIRES.

SPECIFICATION forming part of Letters Patent No. 340,127, dated April 20, 1886.

Application filed January 23, 1884. Serial No. 118,385. (No model.)

To all whom it may concern:

Be it known that I, EDWARD KENDALL, of Cambridgeport, in the county of Middlesex and State of Massachusetts, have invented a new and useful Method of and Apparatus for Extinguishing Fires, of which the following, taken in connection with the accompanying drawings, is a specification.

My invention relates to an improved method of and apparatus for extinguishing fires in buildings; and it consists in certain novel arrangements and combinations of devices, which will be readily understood by reference to the description of the drawings and to the claim to be hereinafter given.

Figure 1 is a partial vertical section of a building with my invention applied thereto. Fig. 2 is a partial vertical section of the same on line xx on Fig. 1, and Fig. 3 is a detail illustrating the devices for automatically controlling the operation of the water-supply pump.

A and B are two cylindrical tanks, made of boiler-iron of sufficient strength to withstand with safety a pressure of, say, two hundred pounds per square inch, and connected together at their upper ends by the pipe C, which is provided with the valve or gate C', by which communication between said tanks may be closed at will. The tank A is filled with water, and the tank B with air compressed to, say, ten or fifteen atmospheres, which pressure is transmitted through the pipe C to the upper surface of the water contained in the tank A whenever the valve C' is opened.

D is a stand-pipe communicating at its lower end with the interior of the tank A, and extending upward through the several stories of the building, and having its upper end closed. This pipe D is located near a vertical tier of windows, E, and is provided upon each story with one or more branch pipes, D', and cocks D'', to each of which is coupled a section of hose, F, provided with a suitable discharge pipe or nozzle, α , said hose F and cocks D'' being so arranged relative to the windows that they may be readily reached from the exterior of the building through said windows, if necessary.

The tank A is filled with water by means of the pump G, which communicates with the interior of the tank A through the pipe b, as shown.

The pipe D is provided with a pivoted gate, c, (shown in section in Fig. 3,) which, when the water in said pipe is in a quiescent state, remains in the position shown in said Fig. 3, but is moved upward around its axis as soon as an upward current of the water in said pipe takes place.

The gate c is mounted upon a short rocker-shaft, c', one end of which projects through the casing H, and has firmly secured thereto the arm d, the movable end of which is connected to one end of the rod e, the opposite end of which is pivoted to the movable end of the arm f, secured to the stem of the valve I of the steam-pump G, as shown in Fig. 1.

The tank B may be filled with air under pressure by means of an air pump or compressor, if desired, or by filling the tank A with water with the valve or gate C' open, by which operation the air contained in the tank A is driven over into the tank B, nearly doubling its pressure, when the valve C' is closed, the cock J is opened, and the water is drawn from the tank A through the cock K. When the water is all withdrawn, the cocks J and K are closed, the valve C' is opened, and the pump is again set in motion and the tank A is again filled with water, thereby forcing the air contained therein over into the tank B and adding another atmosphere to the pressure therein. These operations may be repeated till the desired pressure is obtained within the tanks A and B, when the apparatus is ready for use in case of fire, and will remain so for an indefinite period or until the occasion arises for its use.

L L are balconies extending along the front of the second and third floors of the building, and connected by ladders M M, to serve as a fire-escape.

In some cases I propose to use sprinklers in the several rooms or on the several floors of the building, in which case one or more pipes, N, branch from the stand-pipe D and extend upward—one to each of the floors or stories of the building—and communicate with the horizontal sprinkler-pipes O O, arranged just beneath the ceiling on each story, as shown.

P P are cocks or valves for controlling the passage of water through the pipes N N.

The operation of my invention is as follows: The tanks A and B being charged to the desired pressure and a fire being discovered in

- the building, the party discovering it, if in the building, would make his way to the hose-pipe F that is most convenient to the fire, either by going from room to room or by stepping out of a window upon one of the balconies L, and opening or breaking the window nearest to said hose, and, reaching in, seize and uncoil the hose, and then open the valve or cock D², when the pressure upon the upper surface of the water in the tank A would cause the water to be forced therefrom up the pipe D and be discharged through the hose-pipe in whatever direction the operator saw fit to direct it. The starting of the column of water up the pipe D would cause the pivoted gate c to be moved upward about its axis, thereby opening the valve for admission of steam to the steam-cylinder of the pump G, thereby setting said pump in motion and causing it to force water into the tank A, to supply the deficiency occasioned by the removal of the water discharged from the hose-pipe upon the fire and keep up the pressure in the tanks A and B.
- If the apparatus is fitted up with the sprinkler-pipes O O, the operator opens the valve P in the pipe N leading to the room or floor upon which the fire is raging, when the pressure in the tanks A and B will cause the room or floor where the fire is to be flooded with water, and at the same time the pump G will be set in operation to pump water into the tank A and maintain the desired pressure, as before described.
- The apparatus shown and described is represented as applied to a large mill or factory where steam-power is used, and where steam sufficient to work the pump G is maintained during the night; but I do not wish to be limited to such a use of my apparatus, as it is obvious that my air and water tanks and pipe system may be used to great advantage in buildings where no steam or other power is available during the night, if only the requisite means are at hand for filling the tanks with water and air at the desired pressure during the day-time, so that the apparatus is ready charged at a pressure, say, of two hundred pounds per square inch.
- If a fire occurs, the operator has only to open the necessary cock or valve, the apparatus being ready for instant use, when the

water in tank A will be discharged upon the fire till none remains in said tank, at which time the pressure will have been reduced to 55 one hundred pounds per square inch, when its usefulness will cease till the tank A can be again filled with water.

If the tanks A and B are made of considerable capacity and are kept properly charged, 60 they would in many cases be sufficient to extinguish the fire without the aid of the fire department, and in all cases where the fire is discovered in season for the apparatus to be available it would materially aid in the extinguishment of the fire.

I am aware of the employment for extinguishing fires of chemical engines, so called, in which a pressure is generated in a receptacle containing a liquid by the commingling of 7 certain chemicals; and I do not claim anything contained in such apparatus.

It is obvious that substantially the same effect may be produced by using a single tank filled about half-full of water, and having the 75 remaining space filled with compressed common air; and therefore I do not wish to be limited to the use of two tanks, although I prefer to use two tanks, as being more convenient than one.

What I claim as new, and desire to secure by Letters Patent of the United States, is—

In an apparatus for extinguishing fires, the combination of one or more tanks or receptacles filled with air and water under pressure, a 85 discharge-pipe leading therefrom to the top of the building, a pump for supplying water to said tank, a valve or gate in said discharge-pipe arranged and adapted to be operated by the movement of the water through said pipe, 90 and a rod connecting said valve or gate with the valves of the pump, whereby the upward flow of water through said discharge-pipe will cause said pump to be set in motion, substantially as and for the purposes described.

In testimony whereof I have signed my name to this specification, in the presence of two subscribing witnesses, on this 21st day of January, A. D. 1884.

EDWARD KENDALL.
